UNITED STATES PATENT OFFICE.

JOHN H. IVEY, OF PONCA CITY, OKLAHOMA, ASSIGNOR OF ONE-HALF TO LORY J. MILDREN, OF PONCA CITY, OKLAHOMA.

WRENCH.

Application filed March 6, 1926. Serial No. 92,847.

This invention relates to improvements in wrenches.

The primary object of this invention is the provision of a wrench structure embodying means to facilitate the extraction of a nut from the socket thereof, and to cleanse the socket of dirt and other foreign materials.

A further object of this invention is the provision of an improved wrench, of the socket type, having a novel and compact plunger construction associated therewith, operable in the socket of the wrench, to facilitate nut extraction from the socket, and to cleanse the socket from time to time of accumulations of foreign materials, such as dirt and the like.

Other objects and advantages of this invention will be apparent during the course of the following detailed description.

20 In the accompanying drawing, forming a part of this specification, and wherein similar reference characters designate corresponding parts throughout the several views,

25 Fig. 1 is a side elevation, partly in longitudinal section, of the improved wrench and its nut extracting construction;

Fig. 2 is an enlarged edge elevation of the upper portion of the wrench, showing operating features thereof; and

30 Figs. 3 and 4 are side elevations of different types of wrenches with which the improved nut and dirt extractor may be associated in the relation illustrated in Fig. 1.

In the drawing, wherein for the purpose 35 of illustration is shown only a preferred embodiment of the nut extractor arrangement as used with wrenches, the letters A, B, and C may designate different types of wrenches, with which the improved means D may be used for the purpose of forcing nuts or foreign accumulations from the socket of the wrench.

The wrenches A, B, and C are of the type 45 which include the preferably straight elongated stock portion 10, having the enlarged socket in the lower end thereof, and the preferably right-angled crank arm 12 at the upper end thereof. The socket portion 11 of the stock 10 is provided with the nut-receiving opening 12^a therein, which is polygonal in cross-section, to suit the nut or bolt head which the same is to receive, and this socket opening 12^a is sufficiently deep, in order to

accommodate an extractor head 13 of the plunger construction D, as will be subsequently described.

The stock portion 10 is preferably straight, and the same in the upper end thereof is provided with a relatively large passageway 14, extending approximately halfway along the stock 10, and having an opening 15 at its upper end, at the juncture of the stock 10, with the crank arm 12. The lower portion of the stock 10 is provided with a reduced passageway 16 alining axially with the passageway 14, and at the juncture of the passageways 14 and 15 an annular upwardly facing shoulder 17 is provided.

The handle of the wrench may be finished in any of the different ways illustrated in Figs. 1, 3, and 4 of the drawing. For the old type of wrench the same comprises an upwardly-extending handle extension 25, at the free end of the crank arm 12, extending outwardly at right angles therefrom, opposite the stock 10, and having a hand-engaging knob 26 at the free end thereof.

In the form B, the crank arm 12 thereof is provided with the right-angled extension 28 at the free end thereof, extending opposite from the stock 10, and at the free end of the portion 28 a connecting arm 29 is provided extending parallel with the crank arm 12. The arm 29 at its free end has a hand-grasping extension 30, with a hand knob 31 thereon; the extension 30 alining axially with the stock portion 10.

In the form of wrench C, which is the T-shaped type, the crank arm 12 has a head 35 thereof which is bent in the form of a T, 90 providing a hand-engaging loop which extends at both sides of the axis of the stock 10.

Referring to the plunger construction D for extracting nuts and foreign materials from the socket opening 12, the same includes a relatively small diametered plunger rod 36, extending longitudinally in a slideable relation through the passageways 14 and 16, and at its lower end having the extracting head 13 rigid therewith, and slidably located in the socket opening 12^a. At its upper end the plunger rod 36 may be screw-threaded as at 40, for detachably receiving an enlarged plunger guide head 42, snugly sliding in the upper portion of the passageway 14, and extending upwardly

thru the open end 15 of said passageway, and projecting upwardly beyond the crank arm 12, and of course outwardly of the stock 10, as illustrated in the various figures of the drawing. The upper end of this plunger head 40 may be flat and convexly arcuated as edge 43. A compressing spring 44 is placed in the passageway 14 of the stock, resting on the shoulder 17 at its lower end, and engaging against the lower surface 45 of the guide portion 42 of the plunger device at its upper end, and normally tending to urge the plunger construction upwardly in the passageway of the stock 10, so that the extractor head 13 is maintained in the upper portion of the socket opening 12^a, as illustrated in Fig. 1 of the drawing.

The extractor head 13 is polygonal in cross-section, snugly fitting for a sliding engagement in the opening 12^a, and when sliding therein there are no free spaces at the edges thereof into which dust and accumulation may pass, so that it can be readily understood when the extractor head 13 is reciprocated in the opening 12^a, all foreign accumulations, and nuts or bolt heads may be forced outwardly from the opening 12^a.

An operating lever 50, preferably of sheet metal, is pivotally mounted upon the crank arm 12, remote from the stock 10. This operating lever 50 is preferably bent into U-shaped formation, with side legs 51 disposed at opposite sides of the crank arm 12. At the end of the lever 50 adjacent the handle 25 of the wrench the legs 51 of the lever 50 are pivoted by a pin 54. The lever 50 extends towards the stock from its pivoted end, and at its free end it is provided with a hook-shaped socket end 55, in which the upper convex edge 43 of the plunger guide 42 is received. The spring 44 forces the plunger upwardly into engagement with the lever 50, at its end 55, and forces the lever 50 at its free end upwardly, until a rear edge 56 of the lever abuts against the top edge of the crank arm 12, to limit the upward movement of the crank arm 50 to a divergent acute angular position with respect to the crank arm 12, and to maintain the spring 44 under an initial compression.

As to the operation of the wrench, to extract dirt or a nut, or a bolt head from the socket opening 12^a, it is merely necessary for the operator to press downwardly upon the lever 50, when the same is grasped in the hand, the fingers of the hand engaging about the crank arm 12, and upon closing of the hand the lever 50 will be moved towards the crank arm 12, and consequently the plunger guide portion 42 forced downwardly, incident to a cam engagement with the lever 50, and thru the plunger rod 36 the extractor head 13 will be forced downwardly or outwardly towards the outer end of the socket opening 12^a, for extraction purposes,

as can readily be understood. The spring 44, of course, returns the plunger to the position illustrated in Fig. 1 of the drawing.

Various changes in the shape, size, and arrangement of parts may be made to the form of invention herein shown and described, without departing from the spirit of the invention or the scope of the claims.

I claim:

1. In a wrench the combination of a tubular stock having a socket at one end thereof and a laterally extending crank arm at the opposite end thereof, a plunger reciprocable in said tubular stock having an extractor head operating in said socket, said plunger at the end thereof opposite the socket and at the juncture of the stock with said crank arm being extended outwardly of the stock and crank arm, a lever pivoted on the crank arm having a sliding cam engagement with said plunger to cause the plunger to move longitudinally in the stock and the extractor head to move along said socket upon movement of the lever upon said crank arm, and spring means operating on the plunger normally tending to force the same outwardly against said lever and to maintain the extractor head retracted at the inner end of said socket, said lever having an abutment thereon for engaging the crank arm to limit the action of the spring on the plunger to maintain said spring under an initial tension when the extractor head is retracted in said socket.

2. In a wrench the combination of a tubular stock having a polygonal socket at one end thereof, an extractor head reciprocable in said socket, a plunger rod connected with the extractor head reciprocable through the tubular stock, a guide member at the upper end of the plunger rod extending exteriorly of the stock at the end of the stock opposite said socket, spring means in the tubular stock engaging the stock at one end in an immovable relation and engaging the plunger guide at the opposite end and acting on the plunger guide to force the same outwardly from its adjacent end of the stock and to maintain the extractor head retracted in the inner end of said socket, a crank arm formed on the stock laterally of the stock at the end of the stock from which the plunger guide extends, and an operating lever pivoted on said laterally extending arm having a sliding engagement at its free end upon said plunger guide, said laterally extending arm having a handle at the free end thereof, and the lever being formed to engage the laterally extending arm to limit the movement of the lever responsive to spring action to maintain the spring under an initial compression.

3. In a wrench the combination of a tubu-

lar wrench body having a socket at an end thereof, the tubular wrench body having a passageway therethrough, the wrench socket being alined with said passageway and having an entrance opening at an end thereof alining with the passageway, a plunger reciprocably mounted in the passageway of the tubular body, an extractor head connected with the plunger and operating in said wrench socket, spring means operating on the plunger to maintain the extractor head retracted into the inner end of the socket opposite the entrance end, and lever means pivoted on the wrench body and operating on the plunger to facilitate movement of the extractor head along said socket.

4. In a wrench the combination of a tubular stock having a passageway therealong and a nut-receiving socket at an end thereof alining with said passageway and provided with an entrance opening alining with the passageway, a laterally extending crank arm upon the stock at the end thereof opposite the socket, a plunger reciprocable in said stock having an extractor head operating in said socket, and hand-engaging lever means pivoted on the crank arm at one end thereof and slidably engaging the plunger at the opposite end thereof for reciprocating the plunger in the stock to move the extractor head in said socket.

5. In a wrench the combination of a tubular stock having a socket at one end thereof and a laterally extending crank arm at the opposite end thereof remote from the socket, said plunger reciprocable in the tubular stock having an extractor head operating in said socket, a plunger adjacent the juncture of the stock and crank arm extending beyond the crank arm, and a pivoted hand-engaging lever pivoted at one end adjacent the outer end of the crank arm and at its opposite end slidably engaging the plunger, said lever having a hand-engaging portion intermediate its pivoted end and the end which

slidably engages the plunger, means to normally elevate the lever beyond the crank arm to receive an operator's hand in a normal grasp of the same and the crank arm, whereby upon pressure being exerted the lever will 50 be depressed for causing a movement of the plunger.

6. In a wrench the combination of a tubular stock portion having a nut-receiving socket at an end thereof, the stock portion having a passageway alining with said socket, a plunger slidable in said passageway and extending beyond the tubular stock portion at the opposite end thereof from the socket, a right-angled crank arm connected 60 on the end of the stock portion from which the plunger extends, an operating hand-engaging lever pivoted at one end adjacent the outer end of the crank arm and at the opposite end slidably engaging the plunger, 65 and spring means normally urging the plunger towards the crank arm and the lever to a divergent relation with the crank arm.

7. In a wrench the combination of a tubular stock portion having a socket at one end thereof and a passageway alining with the socket, a plunger slidable in said passageway and at the end opposite the socket extending beyond the tubular stock portion, a right-angled crank portion on the stock portion 75 at the end thereof opposite the socket, a hand-engaging lever pivoted at one end adjacent the outer end of the crank portion, said lever at the free end thereof being substantially U-shaped in cross-section and providing a socket, the upper end of the plunger which extends outwardly from the tubular stock portion being reduced and slidably received in the socket at the free end of said lever, and spring means operating on the 80 plunger to force the reduced end thereof into the socket of the hand-engaging lever to move the latter into a divergent relation with respect to the crank portion.

JOHN H. IVEY.
